US0D1099842S

(12) **United States Design Patent** (10) **Patent No.:** **US D1,099,842 S**
(45) **Date of Patent:** **** Oct. 28, 2025**

(54) **CONNECTOR**

(71) Applicant: **TE Connectivity Brasil Indústria De Eletrônicos Ltda**, Bragança Paulista (BR)

(72) Inventors: **Gustavo Bonucci**, Bragança Paulista (BR); **Rafael Kazuo Sato Toledo Leme**, Bragança Paulista (BR)

(73) Assignee: **TE Connectivity Brasil Indústria De Eletrônicos Ltda**, Bragança Paulista (BR)

(**) Term: **15 Years**

(21) Appl. No.: **29/872,147**

(22) Filed: **Mar. 7, 2023**

(30) **Foreign Application Priority Data**

Sep. 9, 2022 (BR) 30 2022 004859 3

(51) **LOC (15) Cl.** **13-03**

(57) **CLAIM**

The ornamental design for a connector, as shown and described.

DESCRIPTION

FIG. 1 is a rear, left and bottom perspective view of a connector in accordance with the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate portions of the connector that form no part of the claimed design.
